VENTILATING SPACER

Samuel P. Crane, Great Neck, and Stephen D. Kent, Newburgh, N.Y., assignors, by mesne assignments, to Alpha Research Corp., New York, N.Y., a corporation of New York

Filed June 30, 1959, Ser. No. 824,906
6 Claims. (Cl. 267—110)

This invention relates to coiled wire inner units for ventilating spacers or cushions having two intersecting sets of substantially parallel coiled wire rows and to the manufacture thereof, and relates particularly to the winding of the rows on a border frame and the locking of the rows of coils together.

In the inner spring units here involved, one set of rows of generally circular coils is arranged at right angles to a similar set of rows, and the coils of the rows are interlocked by pressing the various coils laterally together and flattening the coils into generally elliptical form. However, while flattening locks the rows together against excessive displacement, the coiled wire part of the unit does not become stiff but even the locked rows are rather limp and can move to a limited extent relatively to the border frame during handling and use.

The present invention therefore contemplates the provision not only of a lock between intersecting rows but also of an additional lock occurring at random points where the uppermost or lowermost point of the outer wire of two intersecting coils is in contact with the respective uppermost or lowermost point of the inner wire of the intersecting coils, such additional lock comprising an indent in the inner wire in which indent the outer wire is received and held.

The invention further contemplates the formation of the indents at the above mentioned random points of contact of intersecting coils simultaneously with the flattening of the initially circular coils, the outer wires of the intersecting coils being locked in the indents of the inner wires by the inherent resiliency of the inner wires which tend to expand toward their initial circular form, and the outer surface of the resulting coiled structure being relatively level and free of outstanding wires especially at the intersections of the coils where hard raised spots might otherwise be formed.

The invention further contemplates the use of the outer of any pair of the intersecting wires as a die for forming the indent in the inner of the wires, the material of the wires being of such nature that the coils become permanently distorted into the desired shape simultaneously with the formation of the indents, while the shape of the outer or die wire at the intersection is retained unchanged.

The invention further contemplates the provision of a wire unit so wound and shaped from a single length of coiled wire that none of the coils project outwardly beyond the plane tangent to the majority of the outermost points of the coils, the winding proceeding in the same rotary direction or pitch as the pitch of the coils, the corner coil connecting perpendicular rows being distorted to prevent the connecting coil from yielding and retaining an undesirable resilience in spite of the flattening operation, the distortion of the connecting coil also preventing it from resuming its initial position after its release from the flattening pressure thereon and thereby preventing said coil from protruding unduly and forming a projecting lump on the unit.

The various objects of the invention will be clear from the description which follows and from the drawings, in which:

FIG. 1 is a view of a typical seat or back spacer show-

2

ing fragments of the rows of coiled wire of the inner unit and of the covering for the unit.

FIG. 2 is a fragmentary elevational view of intersecting coils showing the indents in the inner coil made by the outer coil.

FIG. 3 is a top plan view of FIG. 2.

FIG. 4 is a fragmentary elevational view of the initially circular coils at an intersection of the rows after the winding has been completed and just as a flattening operation in a press is begun.

FIG. 5 is a similar view showing the coils flattened and the formation of the indent just beginning.

FIG. 6 is a similar view showing the indent completed by compressing the coils somewhat beyond the final shapes thereof.

FIG. 7 is a similar view showing the combined flattening and indenting operation completed and the coils released.

FIG. 8 is a diagrammatic view of a modified form of 20 the unit compressing apparatus showing a pair of moving converging belts instead of a press, the belts being constrained to compress the coiled wire unit.

FIG. 9 is a similar view of another modified form of 25 the compressing apparatus which takes the form of rollers.

FIG. 10 is an elevational view of the winding apparatus for winding the long coil about a border frame into rows and for interlacing the rows.

FIG. 11 is a similar view showing the completion of 30 the winding of one set of rows and the partially wound unit lifted out of its holder ready for turning in the direction of the arrow preparatory to winding the second set of rows.

FIG. 12 is a side elevational view of FIG. 11.

FIG. 13 is a view similar to FIG. 11 showing the unit 35 turned at right angles and the winding of the first row of the second set of rows completed.

FIG. 14 is an elevational view of one form of the distorted corner coil at the junction of two perpendicular 40 rows to lock the junction against displacement.

FIG. 15 is a similar view of a modified form of the distorted corner coil.

FIG. 16 is an elevational view of the unit after it has 45 been wound and before interlacing of the rows.

FIG. 17 is a view of the unit after it has been wound and before interlacing of the rows. The type of spacer to which the present invention pertains is shown in FIG. 1 wherein the finished spacer or cushion 20 comprises an inner coiled wire unit 21 and suitable open mesh covers 22 enclosing the unit and bound together by stitching (not shown) around the edges thereof. The inner unit 21 includes the relatively thick border wire frame 23 and two intersecting sets 24 and 25 each of a number of substantially parallel rows of coiled wire and a length 26 of such wire strung around the border frame.

As best seen in FIGS. 2, 3, 14—16 where the rows intersect, the coils are interlaced or forced into each other thereby being temporarily but insufficiently firmly locked together by the inherent resiliency of the wire coils. To attain a better lock at the row intersections as well as to 55 reduce the height of the spacer to an efficient minimum, the initially circular coils of the rows and border are all flattened and elongated transversely to an approximately elliptical shape as shown in FIGS. 2 and 5—9. At the same time, indents as 27 are made in the inner of 60 the intersecting coils at those points where an outer and inner coil are in contact at the tops or bottoms thereof.

Various forms of apparatus may be employed to perform the flattening and indenting operation. As shown 65 more or less diagrammatically, the apparatus may be a press 28 (FIGS. 4—7), or a pair of moving conveyor belts 29, 30 backed by converging plates 31, 32 (FIG. 8), or

a series of cooperating rollers 33, 34, 35, 36, 37, 38 and 39, 40 (FIG. 9) spaced apart diminishing distances.

After the inner unit has been formed by winding a length of coiled wire about a frame in the manner more fully described hereinafter, the coils are generally circular and the axes of the intersecting rows are substantially coplanar. The partially locked unit is then compressed laterally in any suitable manner. As shown in FIG. 6 such compression proceeds to a point beyond the elastic limit of the wire and causes the coils as 41 to flatten at the tops 42 and bottoms 43 and to form a comparatively sharp break or curve of greatly reduced radius at each of the opposite sides 44 and 45.

Should the wire be relatively resilient because of its thickness, carbon content, acquired work hardness, temper or any of a considerable number of factors governing resilience, then compression of the coils would be materially resisted and would cause only a temporary decrease in the length of the minor axis of the generally elliptical cross section of each coil and would have no other permanent effect beyond flattening the coils to a different permanent height. However, the wire material preferably has such low resilience as to permit a substantial amount of permanent distortion of the coils when the wound unit is compressed to the depth shown in FIG. 6 which is somewhat less than the final depth or height of the coils shown in FIG. 7.

At those random or unpredictable points of contact between the high points 46, 47 of intersecting coils 48, 49 or the low points of contact of intersecting coils, the outer coil as 48 is forced into the inner coil 49 in the manner of a die and forms the indent 27 in the inner coil. The indent is of such depth that the outermost point of the outer coil is coplanar with the outermost points of the inner coil thereby to form a comparatively level top on the unit with no projecting or outstanding wire. When the press releases the unit as in FIG. 7, the indent remains but the coils may expand slightly. Since the spacing between rows, the pitch of the coils and the relation between the coils of different rows may vary to a considerable extent, the points of contact between the crests or valleys of the coils, or in other words between the outermost points of intersecting coils, cannot be accurately determined or made uniform but are more or less haphazard and arranged at random with but little control over the exact positions thereof.

Once the indents are formed, it is obvious that accidental movement of the outer wire out of the indent is substantially resisted by the terminal resilience of the inner coil and the tendency of said coil to expand whereby the indent forms an additional lock for the intersecting coils, making the entire unit firmer and less limp or less likely to sway and hence better able to withstand handling and wear.

As has been indicated, the two sets 24 and 25 of rows of coils are preferably formed by winding a long coiled wire around the border wire or frame 23 to form one set 24 of rows arranged generally in one direction and a second set 25 in a direction substantially perpendicular to the set 24. The frame 23 being initially open, an end thereof is first inserted into the end portion 50 of the coiled wire and the coils are strung along the frame, after which the frame is closed. Because of the extreme length of the coiled wire, the winding of the rows is preferably done by rotating the border frame and thereby advancing the remainder of the length of coiled wire while maintaining it substantially straight and unentangled.

The border frame may be manually or mechanically rotated. As shown in FIGS. 10-13, the frame with the border coils strung thereon is clamped between the upper rotatable channel-shaped holder 52 and the similar lower holder 53 by first raising the upper holder against the action of the spring 54 which urges the holder downwardly into frame clamping position. The bracket 55

supports the shaft 56 of the upper holder for vertical and rotary movement and is also provided with notches 57 spaced apart vertically and serving as gages to determine the spacing of the rows. The lower holder 53 may be continuously rotated in one direction, and stopped or reversed when desired under the control of the operator, by the use of a suitable motor and clutch (not shown) operating through the belt 58 and pulley 59 on the shaft 60 for the holder.

The length of coiled wire may be held in the hand or passed through the tube 61 lined with suitable friction material to brake any too rapid advance of the coils and to keep the coiled length taut. After the extreme end 62 of the coiled wire on the frame is secured to the beginning of the first row 63 (FIG. 10) of coils, the coils constituting the first row being behind and at the lower part of the frame, rotation of the holders is begun in the direction of the arrow while the tube 61 is held by the operator in the bottom one of the notches 57 of the bracket 55. It will be noted that the direction of rotation is counter clockwise in plan view because the pitch of the coils is that of a left hand screw, that is, the coils recede from the observer in a counter clockwise direction as in a left hand screw. The first row 63 of coils is stretched across and behind the frame before rotation is begun. After the first half turn of the frame, the first row is in front and the second row stretched out behind the frame. To apprise the operator when each turn is about completed, so that the tube 61 may be raised to the next notch above in position to guide the coils into the next row, a thin ribbon spring 64 extends in both horizontal directions from the holder 52. The end 65 of the spring strikes the bracket 55 near the end of each half turn and makes a sound or creates a vibration heard or felt by the operator and constituting a signal, whereupon the operator shifts the tube 61 to the next notch. This operation is repeated until the entire first set of rows has been wound around the frame, after which rotation of the frame is stopped. The next operation is to lock the end coil of the last row 66 of the first set 24 and constituting the beginning of the second set 25 of the rows of coils (FIGS. 11 and 14) before beginning the winding of said second set. Such locking may be performed in different ways as shown for example in FIGS. 14 and 15, but in any case, the locking operation includes distorting the coil 67 at the end of the last row 66 in one way or another. As best seen in FIG. 14, the last coil 67 of the row 66 is locked into an adjacent coil as 68 of the border coils 26 by bending said coil 67 more or less abruptly to form a relatively sharp hook or bend 69 preventing the locked coil 67 from leaving the locking coil 68 under the stress put upon the row 66 when the direction of the rows is changed from one set to the other. The row 66 is not carried around the border frame so that the direction of winding remains that of a left hand screw or left hand pitch. The first row 70 of the second set 25 is perpendicular to the last row 66 of the first set 24 and is on the same side of the frame. Both ends of the first row 70 are locked on the same side of the frame, the last coil 67a being distorted similarly to the first coil 67 and similarly locked into one of the adjacent border coils. The ends of the row 70 being thus locked, the partly wound unit is rotated a quarter turn in the direction of the arrow of FIG. 11. This may be done by first raising the unit out of the lower holder 53 as shown by the arrow of FIG. 12 against the action of the spring 54, after which the frame is re-mounted in the holders in the position of FIG. 13. The tube 61 is held in the uppermost of the notches 57 and rotation of the holder begun in the opposite direction (clockwise in plan view) to wind the second and succeeding rows across the frame. The winding then proceeds as for the first set of rows but in the opposite direction and except that the tube 61 is moved downwardly notch by notch instead of upwardly. When the winding of the second set of rows has been

completed, the last coil of the last row is hooked to an adjacent coil of the border or other rows and the surplus length of coiled wire, if any, cut off to complete the unit, which is removed from the holder.

The rows of the unit, when wound as described or in other directions as may be suitable to secure the same pitch on the coils and the rows, are not firmly interlocked, but are somewhat bowed as shown in FIG. 16 even though the pitch of the rows and the coils are the same. If such pitches were different, the rows would be far more greatly bowed and could not be levelled or straightened owing to the terminal resilience of the end coils of the rows, even though such resilience is minimized by the selection of substantially non-resilient wire strong enough to bear the weight of a person when used in the spacer. In other words, the coils would lie down temporarily under vertical pressure, instead of being crushed or flattened or deformed, and the coils would then spring back substantially into the initial bowed positions thereof to form a thick lumpy unit instead of a level one. However, when the winding is in the proper direction as determined by the rotation of the frame and the movement of the coiled row vertically, the coils are readily interlaced without deformation by raising the hinged plate 71 (FIG. 10) placing the unit on the table 72 and swinging the plate 71 down on the unit to strike the outstanding rows a sharp blow, thereby levelling the upper and lower surfaces of the unit. The flattening and indenting of the coils may now proceed as hereinbefore described in connection with FIGS. 2-9.

Referring now to FIG. 15, the last row 66 of the first set 24 is there shown in a vertical position at the left of the unit, the partly wound unit having been turned not only as shown in FIG. 13 but also up side down to carry the end coil 72 (corresponding to the coil 67 of FIGS. 11 and 13) of the row 66 to a position near the bottom and at the front of the unit. The last coil 72 starting at the front is partly straightened to remove any tendency thereof to become unruly and to stay upright. The coiled wire is then carried a half turn around the border frame to the rear of the unit being sufficiently distorted to permit winding of the second set of rows perpendicular to the first set without changing the direction of rotation of the frame. The winding therefore is of a left hand pitch as required by the pitch of the coils.

It will now be clear that by employing the proper direction of rotation for the frame, starting the winding at the top or bottom of the frame and with the coiled length in front of or behind the frame, locking one or both corner coils at the change from one set to the other by proper distortion of such coils, it becomes possible to attain initial interlacing and later permanent flattening of the coils without danger of the incidence of unruly and unmanageable outstanding lumps. It will also be seen that while the flattening operation alone is effective to lock the rows together by increasing the horizontal diameters of the coils and wedging them in place, the additional lock in the form of indents renders the unit firmer and less limp and therefore more efficient.

While certain specific forms of the invention have herein been shown and described, various obvious changes may be made therein without departing from the spirit of the invention defined by the appended claims.

We claim:

1. In a coiled wire unit for a ventilating spacer, a first set of coiled wire rows arranged in one general direction, a second set of coiled wire rows arranged in a direction generally perpendicular to and intersecting the first set of rows whereby certain coils of intersecting rows intersect each other, the axes of the rows being coplanar

70

and arranged in a plane substantially half way between the crests and valleys of the coils, random crests and valleys of the inner of the intersecting coils being indented toward the plane of said axes by an amount substantially equal to the thickness of the wire of the coils at the points where the crests of intersecting coils meet and where the valleys of intersecting coils meet to provide locking indents at said points, said indents receiving respectively the crests and valleys of the outer of the intersecting coils, the inner coils having sufficient resilience to exert outward pressure upon and to resist outward movement of the respective outer crests and valleys out of the indents thereby locking said crests and valleys against accidental relative displacement.

2. The unit of claim 1, the rows being bent from a single length of coiled wire, the end coil of the last row of the first set of rows being distorted out of its normal shape and interlocked with an adjacent coil not in said row.

20 3. The unit of claim 2, a border frame, the length of coiled wire having the end portion thereof strung on the frame and having the remainder thereof wound in half turns around the frame to form the rows.

4. In a coiled wire unit for a ventilating spacer, a first 25 set of coiled wire rows arranged in one general direction, a second set of coiled wire rows arranged in a direction generally perpendicular to and intersecting the first set of rows, the axes of the rows being substantially coplanar and arranged in a plane approximately half way between the crests and valleys of the coils whereby certain coils of intersecting rows intersect each other, random crests and valleys of the inner of the intersecting coils being indented toward said plane by an amount substantially equal to the thickness of the wire of the unit and receiving 35 respectively the crests and valleys of the outer of the intersecting coils whereby the intersecting coils are locked together against accidental displacement and the outermost adjacent points of the crests are coplanar, and the outermost adjacent points of the valleys are coplanar.

5. In a coiled wire unit for a ventilating spacer, a border frame, a length of coiled wire of sufficiently low 40 resilience to retain the shape to which said wire is bent under pressure exceeding the elastic limit thereof, an end portion of said length being strung on said frame, the remainder of said length being around the frame and comprising two intersecting sets of rows, one set being perpendicular to the other set where coils of one set intersect coils of the other set at random points, the end coil of the last row of the first set of rows having a relatively

50 sharp bend therein passing around the wire of an adjacent coil of the aforesaid end portion and being locked thereto, the coils being of flattened elliptical shape and the inner of the intersecting coils having an indent therein at the crests and valleys thereof, the indents receiving 55 the respective crests and valleys of the outer of the intersecting coils.

6. The unit of claim 5, a border frame, the rows being wound in half turns around the frame from a single length of wire, and an end portion of said length being strung on the frame, the end coil of the last row of the first set of rows being distorted out of its normal shape and interlocked with an adjacent coil of said end portion.
